UNITED STATES PATENT OFFICE.

WILLIAM URIAH COOPER, OF SHELL KNOB, MISSOURI.

BURGLAR-ALARM.

SPECIFICATION forming part of Letters Patent No. 605,779, dated June 14, 1898.

Application filed September 16, 1897. Serial No. 651,881. (No model.)

To all whom it may concern:

Be it known that I, WILLIAM URIAH COOPER, a citizen of the United States, residing at Shell Knob, in the county of Barry 5 and State of Missouri, have invented certain new and useful Improvements in Mechanical Burglar-Alarms; and I do declare the following to be a full, clear, and exact description of the invention, such as will enable others skilled in the art to which it appertains to make and use the same.

My invention has relation to improvements in mechanical burglar-alarms; and the object is to provide a simple, cheap, and reliable device of this class; and to this end the novelty consists in the construction, combination, and arrangement of the same, as will be herein-after more fully described, and particularly pointed out in the claim.

20 In the accompanying drawings the same reference-numerals indicate the same parts of the invention.

Figure 1 is a diagrammatic plan illustrating my mechanical burglar-alarm in which a separate alarm-bell is used for each door or window, and Fig. 2 is a modification of the same in which a single alarm-bell is employed for any number of doors and windows.

1 represents an ordinary mechanical alarm-bell the engagement-shaft of which is provided with a controlling-arm 2, which vibrates with said shaft.

3 represents a vertical trip-lever the free end of which supports the arm 2 and prevents its vibrating.

4 is a spiral spring attached to one side of the lever 3, and 5 is a flexible cord attached to the other side, from whence it is led over a series of small grooved pulleys 6 6, and from 40 the last one of these it is led in a direct line with the line of movement of the window A to a pulley 6', permanently fixed to the lower rail of the bottom sash. This end of the cord is provided with a small hook 9, which engages the eye 7' on the upper sash. Of course when the bottom sash is down and the upper sash is closed the cord is taut, and the lever 3 supports the arm 2 on the escape-shaft and prevents the alarm operating. If, however, 45 the lower sash be raised or the upper sash lowered, the cord 6 will be slackened and the

spring 4 will draw the trip-lever from under the arm 2, which releases the alarm.

12 represents a screw-eye fixed in the window-frame at approximately the same point 55 from the pulley nearest the window, and when it is desirable to use the window without sounding the alarm the hook 9 is detached from the screw-eye 7' and attached to the screw-eye 12 in the frame, which still preserves the tension on the cord and prevents the alarm sounding and at the same time allows a free use of the window.

The same arrangement is used for the door B as described for the window A, and in practice I prefer to locate the alarm 1 in the bedroom of a house, from which the cord can be conducted by the pulleys to the different points all over the house that it is necessary to protect, and it may even be conducted 70 to outbuildings—such as barns, chicken-houses, and the like—as any tampering with the cord will sound the alarm.

It will be understood that if the cord be pulled instead of slackened the same result 75 will take place—that is, if the cord be pulled it will draw the trip-lever 3 forward against the tension of the spring 4 and release the arm 2 to start the alarm—so that in the case of outbuildings the cord need not be secreted 80 or hidden, as its very publicity adds to its effectiveness.

It will also be understood that the device as above described forms an effective automatic fire-alarm system, for if a fire occurs 85 and burns the cord the alarm is sounded, as in the first instance.

On the modification shown in Fig. 2 the cord instead of being attached to the trip-lever 3 is connected to one end of the bar 3, 90 pivoted in a fixed bracket 14, the spiral spring 4 being connected to the opposite end of the bar 3, as shown. 15 represents a rod pivoted to a bracket 16, and it extends horizontally across the path of a series of the bars 3, so 95 that its free end, which is formed with a retaining-recess 17, engages the free end of the arm 2 in such a manner as to support the rod 15 in a horizontal position, as shown, and at the same time prevents the arm 2 from vibrating. A series of these bars 3 is mounted 100 in the bracket 14, corresponding to the num-

ber of points to be protected, and it will readily be seen that if any one of the cords be slackened its spring 4 will retract it, causing its bar 3 to push the rod 15 from out of the path of the arm 2 and release the alarm.

Although I have specifically described the construction and relative arrangement of the several elements of my invention, I do not desire to be confined to the same, as such changes or modifications may be made as clearly fall within the scope of my invention without departing from the spirit thereof.

Having thus fully described my invention, what I claim as new and useful, and desire to secure by Letters Patent of the United States, is—

A burglar-alarm, comprising the bell 1 provided with the controlling-arm 2, the trip-lever 3 having its free end projecting into the

path of the free end of said arm 2, the spring 4 connected to one side of said lever, and the cord 5 connected at one end to the opposite side of said lever and having its opposite end extending under tension over a fixed pulley 6 thence over a pulley 6' mounted on the movable bottom sash and its immediate end provided with a hook 9 adapted to be removably secured to the upper sash whereby a movement of either sash will slacken the cord to release the trip-lever 3 and sound an alarm, substantially as shown and described.

In testimony whereof I hereunto affix my signature in presence of two witnesses.

WILLIAM URIAH COOPER.
